UNITED STATES PATENT OFFICE

2,482,092

ROUNDING MACHINE

Corwin W. Baker, Stoneham, Mass., assignor to
 United Shoe Machinery Corporation, Flemington, N. J., a corporation of New Jersey

Application March 7, 1946, Serial No. 652,721

24 Claims. (Cl. 12—85)

1

This invention relates to machines for performing such operations as rounding or cutting the soles of shoes or other objects, it being especially applicable to a machine of the type of the well-known Goodyear Universal Rounding and Channelling Machine, Model E, which is, in most respects, as disclosed in Letters Patent of the United States No. 1,030,606, Perry, June 25, 1912.

In existing machines of the character above indicated, the contour of the cut made in the forepart of a shoe being operated upon is determined by a forepart-guide engaging the shoe-upper, the position of the guide being varied by one of a number of cam-disks rotated under the power of the machine once for each operating cycle. As the work held in the hands of the operator is advanced by the feed mechanism of the machine, it may be either forced ahead or retarded, depending on the tendency of the operator, slipping between the feeding members. This will destroy the desired synchronism between the rate of rotation of the cam and the rate of advance of the work, causing the form and location of the sole-edge-extension in the forepart of the sole to be inaccurate. An object of this invention is to predetermine and accurately produce such extension. To this end, I combine with a rounding or other knife to which work is advanced, a forepart-guide movable by contact with the shoe-upper in the direction of advance of the work and arranged to vary the relation of the shoe-sole to the knife or other tool which is to perform an operation upon it. The shape of the upper-contacting surface of the guide preferably is related to the desired form of portions of the rounded sole. This guide in the illustrated machine is constituted by an oscillatory cam, the periphery of which provides the work-guide. To enable the operator to obtain different sole-edge-extensions with a single cam device, there is means for varying the contour of the cam. The guide is preferably adapted to operate upon the soles of both shoes of a pair during its successive movement by them in one direction. Between the operations upon the two shoes, the guide is releasably retained by such means as a latch, and there is means, as a spring, for returning the guide to its initial position after the operation upon the second shoe of the pair, in which position it is again releasably retained. The forepart-guide, as herein disclosed, comprises an oscillatory member which may give the maximum sole-edge-extension, with a second member variable in position upon the first and continuing its work-engaging surface to a point

2

of minimum extension, there being means arranged to set and fix the second member in different positions. For operation upon both shoes of a pair, there is one of these variable members upon each side of the member of maximum extension, and all the members are preferably in the form of segments, the two outer segments being adjustable simultaneously and thereafter fixed in position with respect to the intermediate member.

In machines such as now under consideration, a crease-guide governs the relation of the sole to the knife at the shank of the shoe, and therefore the extension of the sole-edge, the forepart-guide being raised. At or near the ball-line, control is shifted, the forepart-guide being lowered at one side of the shoe and lifted at the other, the crease-guide respectively losing and regaining control. Since it is desirable that there shall be no interval during which neither guide is effective, it is a further object of this invention not only to maintain the work under the constant control of the guides, but also to blend one width of sole-edge gradually into the other. In the attainment of this object, there is combined with a rounding knife, a crease-guide and a forepart-guide, a member for controlling the position of the crease-guide, and means for moving the member gradually during the movement of the forepart-guide. At one extreme of this gradual movement, which may be both at the beginning and end, depending upon the side of the sole at which it occurs, the controlling member is moved abruptly to shift control from one guide to the other. This controlling member, in the form of a cam, of which there may be one or more, is herein disclosed as associated with the crease-guide, it also being movable with respect to the crease-guide as a result of movement of the forepart-guide and also after such movement has stopped. The first of these movements effects the graduation in the sole-edge-extension while the second causes the transfer of control from one guide to the other. The cam may be set in different positions, and is shown as contacting with an adjustable abutment-portion upon the forepart-guide when the work is held up by the operator against the crease-guide. At that extreme of movement of the cam when the forepart-guide assumes control of the work, the crease-guide, though no longer active, is left floating in the crease of the shoe, so that it does not disturb the guiding action upon the shoe provided by the forepart-guide.

The accompanying drawings illustrate one embodiment of the invention.

Fig. 1 showing my improved rounding machine in broken front elevation;

Fig. 2 is a side elevation thereof looking from the left in Fig. 1;

Fig. 3, an enlarged perspective view of a portion of the controlling means for the crease-guide;

Fig. 4, a vertical section through the roll and spindle of these controlling elements;

Fig. 5, a side elevation looking from the right in Fig. 1;

Fig. 6, a top plan view of the circuit-controlling means for the latching mechanism of the forepart-guide;

Fig. 7, an enlarged front elevation of the said forepart-guide;

Fig. 8, a partial central vertical section therethrough;

Fig. 9, a perspective view of the forepart-guide-projection by which its initial position is determined;

Fig. 10, a like view of the projection governing the final position of the forepart-guide;

Figs. 11, 12, 13 and 14 show diagrammatically successive relations between the bottom of a right shoe and the crease-guide and forepart-guide; and

Figs. 15, 16, 17 and 18 are similar diagrams for a left shoe.

As in the machine of the previously mentioned patent, the apparatus of this invention has an oscillatory feed-arm 20, against an anvil upon which cuts a reciprocating chopping knife 22. The sole-edge being operated upon is grasped and advanced step by step, through the action of the feed-arm, upon the welt-side of the sole-edge, and an opposed oscillatory bottom-rest or block 24. This block may carry a knife 26, which, during each return stroke of the block, cuts a channel in the sole. The location of the work with respect to the chopping knife and channel-knife, and therefore the sole-edge-extension and the relation thereof to the channel in the sole, is determined by a crease-guide 28 at the shank and by a forepart-guide F, the arrangement and control of these guides being the subject of the present invention.

As far as the form of the crease-guide 28 is concerned, it may be conventional, of U-shape, and secured at 32 for vertical adjustment upon the end of an arm 34 pivoted at 36 upon the head or frame 38 of the machine. The member 28 and the arm to which it is fixed may be considered as together constituting the crease-guide. The extreme downward movement of the crease-guide, which is under the influence of gravity, is limited by a link 40 (Fig. 5) pivoted at its lower extremity to the arm 34 and having at its upper end a longitudinal closed slot 42, through which passes a stop-projection 44 from the head. At its extreme of upward movement, the arm 34 engages a vertical stop 46 threaded through a frame-bracket 48. This so limits the elevation of the crease-guide that the inner edge of the bottom of the U shall always be spaced vertically from the end of the feed-arm. The position of the crease-guide, when it is effective to determine the width of the sole-edge, is under the control of the forepart-guide, which is designated as a whole by F and which will now be described.

Rotatable in the frame is a horizontal shaft 50, to which is secured an angular arm 58 which first extends forwardly, then upwardly and then again forwardly where it carries a horizontal

section 60 adjustable upon the body of the arm by slot-and-screw connections 62. At the forward extremity of the section 60 is a downwardly and inwardly inclined guideway 64 in which is clamped, by a setscrew 66 threaded through the side of the guideway, a bar or slide 68 furnishing a support for the forepart-guide F. The adjustment of the arm-section 60 at 62 allows the forepart-guide to be adjusted in a generally horizontal direction, so it may move in the proper close relation to the outer face of the crease-guide 28. To enable the operator to set this guide readily to give different maximum sole-edge-extensions, the guideway carries a scale 70 which may be graduated, as in thirty-seconds of an inch (Fig. 7). Over this scale an index-point 72 is movable, its upwardly and then downwardly extending shank 14 being clamped by a setscrew 76 in the upper end of the slide 68. Secured to the shaft 50 is an arm 80 (Fig. 2), from which a tension-spring 82 extends to a bracket 84 at the rear of the frame. This holds the guide F normally raised in its inactive position. Extending upwardly from the shaft 50 at the side of the machine opposite the arm 58 is an arm 86 (Fig. 5), and pivoted to this arm at 88 is a link 90 joined at its opposite end to an arm 92 fast upon a shaft 94 rotatable in the frame parallel to the shaft 50. At the opposite end of the shaft 94 an arm 96 is attached and, rising from the forward extremity of this arm, is a post 98 passing through an opening in an arm 100 loosely mounted upon the shaft 94. The post is provided with a head 102 limiting the upward movement of the arm 100, which is urged yieldably away from the arm 96 by an expansion-spring 104 surrounding the post. From the forward end of the arm 100 depends a link 106 leading to an unillustrated treadle. Upon depression of the treadle, the arm 100 is first turned clockwise (Fig. 2), carrying the arm 96 with it and, through the elements 94, 92, 90, 86 and 50, turning the arm 58 in the same direction. This lowers the forepart-guide F to an extent limited by a stop-screw 108 threaded through the arm 80 and contacting with a frame-bracket 110. After the downward movement of the guide F has been thus arrested, continued treadle-depression rotates the arm 100 about the shaft 94, the spring 104 yielding. The effect of this movement will now be described.

Projecting from the outer side of the crease-guide-arm 34 is a stud 118 about which a cam-disk 120 is arranged to turn. Upon the periphery of the cam-disk are a plurality of crease-guide-controlling cam-surfaces. Of these, in the present instance, three are designed for active use; one, designated as 122, is shown as concentric, a second, 124, is inclined outwardly in a counterclockwise direction (Fig. 2), and the third, 126, inclined inwardly. At the forward end of each of these surfaces is a depression 128 in the periphery of the cam-disk. As the operator holds the crease of a shoe up against the guide 28, the cam-surface which has been placed upon will press against an abutment-roll 130. The roll is rotatable upon a bearing member 131, into which is threaded a spindle 132 (Figs. 3 and 4), guided for vertical movement without rotation in a block 134. This block, in turn, is guided at 136 for adjustment along the outer face of the arm 80 of the forepart-guide, it being secured in place by a slot-and-screw connection 138. The height of the roll may be varied upon rotation of the spindle 132 through a finger-piece 140 upon its upper extremity, while its position

tangentially of the cam-surfaces upon the cam-disk 120 may be changed by adjustment of the block 134. The roll may thus be brought into the desired relation to any one of the cam-surfaces with which it is to coöperate. The axis of the roll substantially coincides with that of the pivot-shaft 50, so during the oscillation of the forepart-arm 58 the position of the roll is not materially affected. The cam-disk 120 can be set so that one or another of the cam-surfaces is brought adjacent to the roll 130. For this purpose there is an opening 142 in the cam-disk for each cam-surface, each opening being adapted to receive a pin 144 clamped in place in the end of a link 146, which is pivoted to the lower extremity of a downward extension 148 from the arm 100 below its pivotal point. As the forepart-guide F is lowered by the clockwise rotation of its arm 58 upon depression of the rod 106, the arm-extension 148 swings to the left (Fig. 2). This, through the link 146, turns the cam-disk 120 counterclockwise, the upmost cam-surface being held in contact with the roll 130 by the work, pressed upwardly against the crease-guide 28. As this cam-surface is shifted along the abutment-roll, its form, according to the selection made, will cause the arm 34 and the crease-guide 28 to remain at rest, to rise or to fall. Therefore, until the forepart-guide in its descent assumes control of the width of the sole-extension, such control is maintained by the crease-guide, and, according to the cam-surface which governs it, the form of curvature of one portion of the sole-edge into the other may be determined. When the forepart-guide has reached the end of its downward travel and is thus ready to position the work, movement of the arm 96 ceases, but depression of the rod 106 continues to turn the arm 100, the spring 104 yielding. This so rotates the cam-disk 120 that the depression 128 at the end of the active cam-surface comes beneath the roll 130. The space provided by the depression frees the arm 34 from the retaining action of the roll, leaving the crease-guide 28 free to float in the crease under the influence of its weight without any locating effect upon the work.

Now to describe the guide F, which is to control the sole-edge-extension about the forepart of the shoe and referring particularly to Figs. 7 to 10, the slide 68 has projecting outwardly from it at right angles a stud 156, about which the casing 158 of an antifriction bearing may oscillate. Fast upon this casing is a carrier-disk 160, which has an outward projection 161, the arcuate peripheral end 162 of which furnishes the work-locating surface for the maximum edge-extension. At the left of this guide member 162 is an arcuate guide member 164 for a right shoe, and at the right of the member 162 a similar guide 166 for a left shoe. Each of the members 164 and 166 has an inward projection 167 which telescopes upon an arm 168 extending outwardly from the periphery of the disk 160. The projections and arms are so curved that, as each projection telescopes upon its arm, the corresponding member 164 or 166 is swung about a point closely adjacent to the end of the central guide member 162. The positions assumed by these outer members 164 and 166 in their adjustment may be between an outward extreme, in which their peripheries continue that of the member 162 along arcs of equal radii, and an inward extreme, in which they are inclined inwardly from the member 162. In the latter case, the slope of

the members 164, 166, resulting from their eccentricity with respect to the member 162, corresponds to the desired variation in the sole-edge-extension. The result of this arrangement is to furnish an adjustable work-locating cam having peripheral guide-surfaces for the foreparts of both shoes of a pair which will produce a sole-edge-extension uniform in width throughout its control by the device F, or one which increases variably between its extremities. To adjust the members 164 and 166 together, so they have similar effects upon the two shoes of a pair, two pinions 170, 170 are rotatable about studs 172, 172 set in the disk-projection 161. Each of the pinions is pivotally connected by a link 174 to the projection from either the member 164 or 166, while one of the pinions has attached to it an arm 176. The inner end of the arm has threaded through it a screw 178 by which it may be turned, or the screw may be caused to bear upon an annular surface 180 of the disk 160 to fix the arm in the position to which it may have been moved. Therefore, by a single actuation of the arm the guide members 164 and 166 may be swung simultaneously about their inner points adjacent to the member 162 to give, at their opposite ends, different minimum sole-edge-exten-

For operation upon a pair of shoes, the guide device F is initially turned to its extreme counterclockwise position and is there held temporarily for release by the operator, the outer extremity of the member 164 furnishing the effective guide for a right shoe. It then turns, under the influence of the work, until the member 162 comes into contact with said work, when it is again temporarily retained for the completion of the operation upon the right shoe. The member 162 then locates the left shoe initially, after which release of the device F permits the member 166 to be turned by engagement with the work, the device coming to a stop to allow the completion of the operation upon the left shoe under the control of the outer extremity of the member 166. Thereafter, the device is returned automatically to its initial position. For thus controlling the guide device F the following means is provided.

In an annular groove in the outer face of the disk 160 is a torsion-spring 184. One end of this spring is attached at 186 to a wall of the groove, while the other end is fixed to a pin 188 set in the slide 68. The spring is held against displacement from the groove by cross-bars 190 and its force is exerted to draw a stop-projection 192 from the periphery of the disk against a latch 194 (Fig. 8). The projection is adjustable circumferentially of the disk 160, it being upon a segment 196 recessed into the periphery and provided with a lug 198 extending along the side of the disk and slotted to receive a clamping screw 200 (Fig. 9). In the segment is a depression 202 which the latch 194 engages to retain the guide F positively against reverse movement. When the guide is shifted, under the influence of the work, to the opposite extreme of its travel, a projection 204 limits its movement. This projection is adjustable, similarly to the projection 192, as is best shown in Fig. 10, but is without the accompanying depression. Substantially midway between the projections 192 and 204 there is a depression 206 in the periphery of the disk 160. The latch 194 for the disk projects from the inner side of an arm 208 pivoted upon the slide 68 and extending inwardly therefrom

(Fig. 8). The arm has an extension 210, and joined to this and to the end of the stud 156 is a tension-spring 212 which holds the latch yieldingly against the periphery of the disk, so it may enter the depressions 202 and 206. The latch may be raised from the depressions at the will of the operator. For this purpose, an upward extension 214 of the forepart-gage-arm 86 carries a solenoid 216 (Fig. 5), the normally lowered plunger 218 of which has secured to it an arm 220 extending forwardly beneath the latch-arm-extension 210. In circuit with the solenoid is an unillustrated source of current and a switch 222 (Figs. 1 and 6), normally open. Supported upon the frame-column 224 is a bracket 226 clamped at 227 for adjustment fore and aft of the machine, this carrying a laterally adjustable bracket 228 clamped at 229 and to the forward extremity of which is hinged a knee-lever 230. By varying the positions of the two brackets the lever may be brought to a position convenient for actuation by the operator to close the switch, energize the solenoid, and trip the latch 194 to release the guide device F.

In describing the operation of the machine, there will be outlined the action of the elements upon the right and left shoes of a pair in which the sole is to have a certain extension at both sides of the shank, a less extension along the forepart between the inside ball-line and the outside tip-line, and a gradually increasing extension from the outside tip-line to the outside ball-line, there to merge into the edge at the shank. This particular relation of edge-widths is taken only for the purpose of illustration, the form of the rounded sole produced depending upon the shape and adjustment of the members 164, 166 and the contour of the chosen controlling surface on the disk 120. In each of Figs. 11 to 14, inclusive, representing the operations upon a right shoe, and Figs. 15 to 18, inclusive, the corresponding operations upon a left shoe, a indicates the outline of the shoe-upper (as viewed from above) which engages the guide device F, b the crease-line which receives the guide 28, c a block-sole attached to the upper and which is to be rounded, and d the line along which the chopping knife 22 has operated to round the sole, as determined by the guides 28 and F. The maximum extension of the forepart-sole-edge has been arranged for by adjustment of the guide member 162 through variation in the location of the slide 68, and the minimum extension by simultaneous adjustment of inclination of the members 164 and 166 through actuation of the arm 176. The crease-guide 28 is in its lowest position, free to rise as the work is pressed against it, to an extent determined by the contact of a selected one of the cam-surfaces 122, 124 and 126 upon the disk 120, with the abutment-roll 130 adjustable upon the forepart-guide-arm 86. It will be assumed that the chosen surface is that designated as 124, which gradually decreases in radius from left to right in Fig. 2. The guide device F is in the extreme position of its counterclockwise movement about the axis of the disk 160, as viewed from the front of the machine, where it was locked by the engagement of the latch 194 within the recess 202 after the preceding pair of shoes had been operated upon, and is raised to its inactive relation by the spring 82.

The operator applies the crease of the right shoe to the guide 28, lifting this until it is stopped by the left-hand end of the surface 124

engaging roll 130, and allows the feed-arm 20 and the bottom-rest 24 to grip and feed the work forward from right to left. The rounding cut is started slightly behind the inside heel-breast line (at h, Fig. 11) so that the guide 28 will be properly seated in the crease and the desired sole-edge-extension obtained when the cut reaches the heel-breast line. The chopping knife, therefore, rounds the sole at the shank to the width indicated near the beginning of its cut in Fig. 11. As the inside ball-line (approximately at e) approaches the operating point, the treadle is depressed by the operator and the device F thereby lowered (Fig. 12). As the arm 100 is turned by the treadle-rod 106, the link 146 rotates the cam-disk 120 so the diminishing cam-surface 124, acting against the abutment-roll 130, permits the upward pressure of the work to gradually lift the crease-guide. Under the control of the cam-surface 124, the width of the edge-extension gradually decreases and, as the device F arrives in active position and its descent is arrested by the stop 108, the final movement of the arm 100, as the spring 104 yields, completes the rotation of the cam-disk. This brings a depression 128 beneath the roll 130, so the crease-guide 28 is abruptly released when the roll 130 rides off the corner of the cam-surface 124 adjacent to the depression. Although control of the work has passed to the forepart-guide F, the crease-guide is left floating in the crease of the shoe, it extending across the welt. It thus exerts on said welt uniform transverse pressure, avoiding the danger of deforming the surface through indenting it because of partial engagement. The action of the cam-disk 120 causes the shank-extension to blend gradually into the forepart-extension with a predetermined curvature, which is fully governed by the crease-guide, this relinquishing control only when it has been assumed by the forepart-guide. Consequently, there is no period in which ungoverned manipulation by the operator fixes the width of the extension.

Of the device F, the member 164 receives contact of the upper of the forepart of the shoe near its outer extremity, so the sole edge is carried in to its minimum width at the inside ball-line (at e). Since the latch 194 is now in the depression 202, the device F is held against rotation, and the outer end of the member 164 furnishes a temporarily fixed guide for the work until a point near the end of the outside tip-line (at f) is reached, from which the edge should be gradually increased in width to the maximum at the outside ball-line (at g). When the rounding cut reaches the outside tip-line (at f), the operator presses the knee-lever 230 to close the circuit of the solenoid 216. This withdraws the latch 194, so the guide device F is free to rotate. As the work is fed to the left, the member 164 is turned by it and, because of the increasing radius of the member 164 the work is moved down, away from the line of action of the chopping knife. The width of the edge is therefore gradually increased to the maximum extent determined by the member 162, in the vicinity of the outer ball-line (at g) as shown in Fig. 13. Since, in this portion of the operation, the forepart-guide is advanced by and at the same rate as the work, which produces this change in edge-extension as it travels, the operator, by forcing or retarding the feed of the work, cannot destroy the correct relation between the forepart-guide and the periphery of the work, as is the case

when a cam driven under the power of the machine governs the position of a guide past which the work is fed. In the present invention, if the feeding of the work should be accelerated, so too is the rotation of the forepart-guide, and the form and peripheral relation of the sole-extension will be the same for all shoes with any one setting of the forepart-guide. At the outside ball-line (at *g*), the operator releases the treadle, and, as shown in Fig. 14, when the rounding operation runs into the shank the crease guide 28 takes over the control of the shoe from the forepart-guide F, which is lifted by the spring 82. More specifically, the arm 100 is elevated by the springs 104 and 82, and, through the link 146, turns the cam-disk 120 clockwise (Fig. 2), forcing the roll 130 out of the depression 128, so said roll again contacts with the cam-surface 124. Therefore, the work is put promptly under the control of the crease-guide 28, and the cam-surface 124 produces an effect opposite to that at the inner side of the shoe, gradually bringing the width of the edge-extension from the maximum down to the lesser width desired in the shank. The rounding cut continues along the outside of the shank, and is run out of the sole after the outside breast line (at *l*) has been reached. When the device F reached its central position, as above described (at *g*, Fig. 13), the latch 194 entered the depression 206 in the disk 160. Accordingly, when the operator separates the rounded right shoe from the device, the latter is held against rotation.

The left shoe is first positioned by the crease-guide 28 (Fig. 15), from the start of the cut made near the outside breast-line (at *l*) to the outside ball-line (at *g*), the forepart-guide F being raised. At the outside ball-line (*g*) the operator treads to lower the guide F, the maximum-extension member 162 of which engages the shoe-upper (Fig. 16). Similarly to the operation upon the right shoe, rotation of the cam-disk 120, by its connection to the forepart-guide-arm 100 has first allowed the crease-guide to rise gradually, and then to float in the crease just as the guide member 162 is in full control. At this time the operator actuates the knee-lever 230 so the solenoid 216 is energized to remove the latch 194 from the depression 206. As the work is fed forward the device F turns, with the periphery of the member 166 moving with it at the same rate, thus producing accurately the gradual decrease of the sole-extension from the maximum at the outside ball-line (at *g*) to the minimum at the outside tip-line (at *f*). This brings the work to the position of Fig. 17. The projection 204 has now reached the latch 194 and is there held by engagement of the advancing work, so an edge of uniform minimum width is produced from the outside tip-line to the inside ball-line (at *e*). Here, the operator releases the device F (Fig. 18), the cam-disk 120 causing the crease-gage 28 to locate the work for the rounding at the inside of the shank before the forepart-guide has become ineffective. At the inside breast-line (at *h*, Fig. 18), the operation upon the shoe has been completed and it is removed from the machine. As soon as the member 166 left the work, upon release of the treadle, the spring 184 acted upon the disk 160 to rotate it to its initial position, as shown in Figs. 18 and 11, ready for operation upon the right shoe of the succeeding pair.

Having thus described my invention, what I 75 claim as new and desire to secure by Letters Patent of the United States is:

1. In a machine for rounding a sole attached to a shoe-upper, a rounding knife to which the sole is advanced, and a forepart-guide movable in the direction of advance of the work by contact with the shoe-upper and arranged to vary the relation of the shoe-sole to the knife.
2. In a machine for rounding a sole attached to a shoe-upper, a rounding knife to which the sole is advanced, and a forepart-guide having a cam-surface arranged to engage the shoe-upper and being movable thereby in the direction of its advance, said surface also having a slope corresponding to the desired variable extension of the sole edge.
3. In a machine for rounding a sole attached to a shoe-upper, a rounding knife to which the sole is advanced, and a forepart-guide movable by contact with the shoe upper and having a cam surface arranged to position the sole in varying relation to the knife whereby the sole edge is trimmed with a varying extension.
4. In a machine for rounding a sole attached to a shoe-upper, a rounding knife to which the sole is advanced, and a forepart-guide comprising a cam movable by contact with the shoe-upper and having a surface arranged to vary the relation of the sole to the knife, and means arranged to vary the contour of the guiding surface of the cam.
5. A guide for shoe machines comprising a rotatable member having a peripheral work-engaging surface, a second member variable in position upon the rotatable member and having a work-engaging surface in alinement with and continuing that of the rotatable member, and means arranged to fix the second member in different positions.
6. A guide for sole-rounding machines comprising an oscillatory segment having a peripheral work-engaging surface for locating a sole to give the maximum sole-edge-extension, a member variable in position with respect to the segment and having a work-engaging surface continuing that of said segment to a point of minimum sole-edge-extension, and means arranged to fix the member in positions giving different minimum sole-edge-extens.
7. A guide for shoe machines comprising a central oscillatory segment having a peripheral work-engaging surface for locating a sole to give the maximum sole-edge-extension, members movable with the segment at opposite sides thereof and each having a work-engaging surface continuing that of said segment to points of minimum sole-edge-extension, and means arranged to move the opposite members simultaneously to different positions with respect to the segment and to fix them in such positions.
8. A guide for shoe machines comprising a supporting member, a carrier oscillatable upon the supporting member and provided with a work-engaging projection and a guideway in each side of the projection, shoe-engaging members movable in the guideways, and means arranged to move the members simultaneously and to fix them in different positions.
9. A guide for shoe machines comprising a supporting member, a carrier oscillatable upon the supporting member and having a work-engaging surface, a work-engaging member variable in position upon the carrier and cooperating with said surface, and means for urging the carrier to one extreme of its oscillatory movement.

11

10. A guide for shoe machines comprising a supporting member, a carrier oscillatable upon the supporting member and having a work-engaging surface, a work-engaging member variable in position upon the carrier and cooperating with said surface, means for urging the carrier to one extreme of its oscillatory movement, and a latch movable upon the supporting member for retaining the carrier in different positions.

11. A guide for shoe machines comprising a supporting member, a carrier oscillatable upon the supporting member and having a work-engaging surface and spaced stop-projections, a work-engaging member variable in position upon the carrier and cooperating with said surface, means for urging the carrier to one extreme of its oscillatory movement, and a latch movable upon the supporting member for engagement by the stop-projections.

12. A guide for shoe machines comprising a supporting member, a carrier oscillatable upon the supporting member and having a work-engaging surface, a work-engaging member variable in position upon the carrier and cooperating with said surface, means for urging the carrier to one extreme of its oscillatory movement, a latch movable upon the supporting member, stop-projections upon the carrier for engagement with the latch, and means arranged to fix the projections in different positions upon the carrier.

13. A guide for shoe machines comprising a supporting member, a carrier oscillatable upon the supporting member and having a work-engaging surface, spaced projections and spaced depressions, a work-engaging member variable in position upon the carrier and cooperating with said surface, means for urging the carrier to one extreme of its oscillatory movement, and a latch movable upon the supporting member for engagement with the projections and entrance into the depressions to retain the carrier in different positions.

14. A guide for shoe machines comprising a movable support, a carrier oscillatable upon the support and having a work-engaging surface, a work-engaging member variable in position upon the carrier and cooperating with said surface, a latch movable upon the support for retaining the carrier in different positions, means for urging the carrier normally to one extreme of its oscillatory movement, and electrical means mounted upon the support for releasing the latch.

15. In a sole-rounding machine, a rounding knife, a supporting member, a carrier movable upon the supporting member and having a work-engaging surface for locating a sole with respect to said knife to give the maximum rounded sole-edge-extension, means arranged to fix the supporting member in positions giving different maximum extensions, a member mounted upon the carrier and having a work-engaging surface continuing that of the carrier to a point of minimum rounded sole-edge-extension, and means arranged to fix the member in positions giving different minimum extensions.

16. In a sole-rounding machine, a rounding knife, a crease-guide and a forepart-guide each movable to position the work differently with relation to the knife, means for positioning the crease-guide relatively to the knife comprising an abutment associated with the forepart-guide and a member associated with the crease-guide and movable with respect thereto in engagement with the abutment as a result of movement of the

forepart-guide to control the position of the crease-guide.

17. In a sole-rounding machine, a rounding knife, a crease-guide and a forepart-guide each movable to position the work differently with relation to the knife, a means for limiting the work positioning movement of the forepart-guide, a member associated with said crease-guide and movable with respect thereto as a result of movement of the forepart-guide to control the position of the crease-guide, and means for continuing the movement of the member after the forepart-guide has reached the limit of its work positioning movement.

18. In a sole-rounding machine, a rounding knife, a crease-guide and a forepart-guide each movable to position the work differently with relation to the knife, a cam movable with the crease-guide and with respect thereto, an abutment adapted to be engaged by said cam, and means operated in response to the movement of the forepart-guide for moving the cam with respect to said crease-guide whereby the position of the crease-guide is varied.

19. In a sole-rounding machine, a rounding knife, a crease-guide and a forepart-guide each movable to position the work differently with relation to the knife, a controlling member movable with the crease-guide, said member also being movable with respect to the crease-guide for controlling the position of crease-guide, a member actuated by the operator and connected to move the controlling member, and means for transmitting the movement of the operator-actuated member yieldably to the forepart-guide.

20. In a sole-rounding machine, a rounding knife, a crease-guide and a forepart-guide each movable to position the work differently with relation to the knife, the forepart-guide having associated therewith an abutment-portion, an arm for supporting said crease-guide, a cam mounted upon said arm and movable thereon in contact with the abutment-portion, and means for moving the cam.

21. In a sole-rounding machine, a rounding knife, a crease-guide and a forepart-guide each movable to position the work differently with relation to the knife, the forepart-guide having associated therewith an abutment-portion, means for varying the position of the abutment-portion with respect to the forepart-guide, a cam associated with the crease-guide and movable with respect thereto in contact with the abutment-portion, and means for moving the cam.

22. In a sole-rounding machine, a rounding knife, a crease-guide and a forepart-guide each movable to position the work differently with relation to the knife, a cam associated with and movable with respect to the crease-guide, an abutment adapted to be engaged by said cam, means arranged to set the cam in different positions with respect to the crease-guide, and means for, moving the cam.

23. In a sole-rounding machine, a rounding knife, a crease-guide and a forepart-guide each being movable to position the work differently with relation to the knife, and connections between said guides through which the crease-guide is positioned by the forepart-guide, said connections being operable in response to the final movement of the forepart-guide into its operative position to disconnect said guides whereby the crease-guide is permitted to float freely in the crease while the forepart-guide is positioning the work.

24. In a sole-rounding machine, a rounding knife, a crease-guide and a forepart-guide each movable to position the work differently with relation to the knife, and means normally connecting said guides by which the crease-guide is positioned relatively to the forepart-guide, said means including a member which is associated with and is movable with respect to the crease-guide successively to vary the relation of the crease-guide to the forepart-guide and then to release the crease-guide whereby it is permitted to float freely in the crease.
